UNITED STATES PATENT OFFICE.

WILLIAM E. COOK, OF ST. GEORGE, NEW YORK, ASSIGNOR TO PEERLESS INSULATED WIRE AND CABLE COMPANY, OF NEW YORK, N. Y., A CORPORATION OF DELAWARE.

COMPACTING HEAD FOR WIRE-COVERING MACHINES.

Application filed November 29, 1921. Serial No. 518,575.

To all whom it may concern:

Be it known that I, WILLIAM E. COOK, a subject of the King of the United Kingdom of Great Britain and Ireland, residing

5 at St. George, in the borough of Richmond, city of New York, county of Richmond, and State of New York, have invented certain new and useful Improvements in Compacting Heads for Wire-Covering Machines, of which the following is a specification, reference being had therein to the accompanying drawings, which form a part thereof.

10 My invention relates to compacting heads 15 for wire covering machines of a type adapted to apply spirally wound cotton sliver to a conductor wire while said wire is having longitudinal traverse through the machine.

In machines of the type above referred 20 to, after the sliver has been spirally wound upon the wire, the covered wire is passed through a compacting die which is constantly rotated in the same direction as the means applying the sliver to the wire 25 so as to smooth down and compact the sliver and bring the covered wire to approximately the desired diameter, binding strands being applied to the covered wire while the body of sliver is under compaction.

30 The binding strands above referred to may be either in the nature of mere confining strands to hold the sliver in proper position upon the wire until after it has been passed through a tubular braiding machine, 35 or as permanent covering strands so as to dispense with the use of the ordinary covering braid.

Heretofore with machines of this type, the compacting die has been formed from 40 a solid block, thus causing likelihood of the stripping of the covering sliver in the event of substantial kinks in the wire, or of localized enlargement of the diameter of the covered wire, as where a splice has been 45 made in the wire or where, as a result of breakage in the sliver or of the application of a new length of sliver, a slight lapping of the sliver itself in necessitated.

50 This lack of flexibility in the old and well known forms of compacting dies, has resulted in a substantial reduction in the capacity of covering machines, since any stripping of the sliver or disarrangement thereof by the compacting die, necessitates 55 the shutting down of the machine and the

hand-covering of a portion of the wire. Such hand-covering also entails possible variations in the condition of the covering at that particular point of the wire.

With the above conditions in mind, I 60 have produced a compacting head embodying therein a die including therein opposed members, movable toward and from each other in a manner to adapt themselves to any irregularities in the covered wire, while 65 subjecting the sliver on the wire to sufficient pressure under all conditions, to ensure the desired compaction of the sliver.

With a head embodying my invention there is substantially no likelihood of a 70 compacting die stripping the sliver from the wire, and in the event of enlargement in the covered wire due to a splice in the wire itself or slight additional thickness of the sliver, the sliver at this point will be 75 subjected to slightly greater pressure so that substantial uniformity in the diameter of the covered wire will be maintained, although slight variances in such diameter are immaterial since in the final finishing operation, the whole wire will be sized up in a manner to practically eliminate such irregularities.

The pressure exerted by the compacting head may be regulated to secure different 80 densities in the body of covering sliver, which pressure regulating mechanism may be utilized either in setting the machine for different classes of wire or adapting the compacting head to peculiar working conditions about the machine due to variances in the quality of the wire or of the covering head.

The construction of the head is also such 85 that the parts of the die may be separated in their entirety to permit access to the wire, within the die, to correct conditions which will not be corrected by the normal, automatic functioning of the head.

Another characteristic of the invention 90 is the inclusion in the opposed members of the die leading into the smallest interior diameter thereof, of guide openings for the binding strands, whereby these strands will be applied through the exterior of the covering sliver while the same is compacted by the die.

To prevent those binding strands which 95 pass adjacent the pressure regulating mechanism, ballooning and becoming entangled 100

with said mechanism, I provide suitable guide means for said strands formed by said mechanism.

The invention consists primarily in a compacting head for wire covering machines embodying therein a rotatable spindle-carrying platform and a die carried thereby and rotatable therewith including therein opposed members movable toward and from each other and having registering, graduated complementary openings therein and a spring rigging operative upon said members respectively, whereby they will be normally engaged, one with the other, but will automatically separate to accommodate said die to irregularities in the diameter of the covered wire; and in such other novel features of construction and combination of parts as are hereinafter set forth and described, and more particularly pointed out in the claims hereto appended.

Referring to the drawings,

Fig. 1 shows a portion of the rotary head of an ordinary covering machine carrying a compacting head embodying my invention;

Fig. 2 is a plan view of said compacting head;

Fig. 3 is a section on the line 3—3 of Fig. 2 showing the opposed die members in the fully closed position;

Fig. 4 is a similar view showing said members in an opened position; and

Fig. 5 is a section on the line 5—5 of Fig. 3. Like letters refer to like parts throughout the several views.

In the embodiment of my invention shown in the drawings, I have indicated at *a* a portion of the hollow spindle carried by the top frame of a rotating platform carrying the cams containing the cotton sliver with which a conductor wire is to be covered. Said spindle *a* is mounted in a suitable bearing *b* in the frame of the machine and has keyed or otherwise secured thereto so as to rotate therewith, the head *c* having a plurality of spindles *c'* and tensioning devices *c''* for the binding or confining strands *c''* carried by the spools or cops *c''*. This general arrangement is old and well known in the art, it also being old and well known in this art to provide other means for rotating the head than the spindle *a*.

Carried by, and rotatable with, the head *c* are the parts *d—e* of a bi-part base, said parts having respectively a bottom flange *d'—e'* provided with an elongated slot *d''—e''* to permit the separation of the parts *d—e* to an extent to permit access to the portion of the covered wire within the die in the event of the jamming of the machine, or the necessity of getting access to the wire in case of an improper covering thereof with sliver sometimes due to the impossibility of checking the machine sufficiently quickly

to prevent such improperly covered wire entering the die. The flanges *d'—e'* are firmly secured to the head *c* by means of the screw bolts *d''—e''* which, when loosened, will permit a sliding movement of the parts *d—e* toward and from each other.

The two parts *d* and *e* of the bi-part base have respectively the complementary portions *d''—e''* of a cylindrical opening, in axial alinement with the opening in the spindle *a*.

Said bi-part base *d—e* carries a die which includes therein opposed members *f—g* which are so mounted on said base as to be movable toward and from each other in a manner to adapt themselves to irregularities in the covered wire, said members *f* and *g* being normally held in engagement one with the other by means of a spring rigging which will be more particularly referred to hereinafter. The purpose of this rigging is to subject the covered wire passing through the die, to sufficient pressure to secure the desired degree of compaction of the sliver, while permitting an automatic opening of the die to prevent the stripping of the sliver from the wire in the event of variance in the diameter of the covered wire due to a bunching of the sliver or kinks and splices in the wire, or a local increased thickness of the sliver from the lapping of an end of sliver strip upon a portion of the wire already covered.

The members *f* and *g* have therein the complementary portions *f'—g'* of a graduated die opening, which opening merges into a cylindrical opening, the complementary portions *f''—g''* are formed in the members *f* and *g* respectively. Said cylindrical portions *f''—g''* are adjacent the outlet end of the die.

In actual practice, no such stresses as will result in the opening of the die, will occur adjacent the cylindrical portion *f''—g''* of the die opening, since under no conditions will the resistance of the sliver be sufficiently great to open said die until the mass thereof upon the wire has been compacted to substantially the maximum extent for which the die is set. It is apparent that such stresses will have no tendency to open the die until the covered wire is approaching the point where the graduated portion of the opening merges into the cylindrical portion of the opening, the opening of the die resulting from a wedging action by any enlarged or distorted portion of the covered wire.

The die member *f* is pivotally mounted upon the portion *d* of the base by means of the pivots *h—h'* located adjacent the bottom of said member so as to ensure an effective leverage of the spring rigging in closing the die, and the development by said rigging of a pressure normally sufficient to impart the desired degree of com-

paction to the sliver. The bottom of said member *f* is curved as shown at *f*³ so as to permit a free pivotal movement of said member, and the face thereof adjacent the member *g* is cut away as shown at *f*⁴ below the point of pivotal support of the member *f* so as not to interfere with a free movement of said member. The member *g* is provided with a similar curved portion *g*³ and a similar cut-away portion *g*⁴, being pivoted to the base part *e* by means of the pivots *i*—*i'*.

The member *g* adjacent the pivots *i*—*i'* is provided with the oppositely disposed dowel pins *j*—*j'* adapted to enter openings in the member *f* to ensure a proper positioning of these parts in assembling the device and to prevent a loss of register of the portions of the complementary portions of the die opening as a possible result of a shifting of the pivots of either member due to vibration in and about the machine.

The spring rigging heretofore referred to comprises a bracket *k* secured to the member *f* and a bracket *m* secured to the member *g* and oppositely arranged as to the bracket *k*. The bracket *k* has laterally extending arms *k'*—*k*² carrying pins to which are attached the springs *n*—*n'* respectively, a construction by which said springs have a free pivotal movement with relation to said bracket. The other ends of said springs respectively are secured to the flattened screws *o*—*o'* which are slidably mounted in openings in the extensions *m'*—*m*² of the bracket *m*.

Mounted upon the slide screws *o*—*o'* are the hand nuts *p*—*p'* respectively by means of which said springs *n*—*n'* may be tensioned to any desired extent to develop the desired compacting pressure in the die or offer any desired resistance to the separation of the members *f*—*g*.

The brackets *k*—*m* are located adjacent the smallest diameter of the graduated portion of the die opening since the maximum compacting pressure will be reached adjacent this point. It is apparent that the degree of compaction of the sliver will be determined by the tension of the springs *n*—*n'* and that the regulation of this tension is largely a matter of convenience to adapt the same die for work with different grades of wires; but where such regulation is not desired, the mechanism permitting such regulation may be dispensed with.

The manner of mounting the slides *o*—*o'* will permit the disconnection of the springs *n*—*n'* from the member *g* so that when the bi-part base is used, and it is desired to separate the parts *d*—*e* thereof, such separation of the parts *d*—*e* and the members *f*—*g* will not be against the tension of the springs *n*—*n'*. Supplementing the action of the dowels *j*—*j'* in securing the desired proper positioning of the two members *f*—*g*, I pro-

vide the member *e* with dowels *q*—*q'* adapted to enter recesses in the member *d*, or vice versa.

The upper portion of the members *f* and *g* are exteriorly tapered as shown and extending through the walls thereof and opening into the cylindrical portion *f*²—*g*² of the die opening are inclined guide openings *r* through which the strands *c*³ are adapted to pass.

While said strands are normally held taut by the tensioning device *c*², there is a possibility of the strand passing through the opening *r* which is arranged substantially centrally of and above the brackets *m* and *k* respectively, ballooning so as to become entangled in said brackets or the spring mechanism. To obviate difficulty from this source, I provide the bracket *k* with a guide opening *k*³ through which a strand *c*³ is adapted to pass, and the bracket *m* with a similar guide opening *m*³ through which the strand passing through the diametrically opposite opening *r* is adapted to pass.

The conditions are such that there is little likelihood of other strands than those referred to being entangled in the spring rigging so that guides supplementing the other openings *r* are not required.

The advantages of arranging the openings *r* as shown are that the various strands will be accurately and evenly applied to the covered wire and will be applied thereto while said wire is compacted to the maximum extent. Hence any expansion of the sliver covering after the covered wire leaves the die will be limited to the portions of the sliver exposed between said strands, which is highly desirable, particularly when these strands constitute the covering for the wire, as such expanded portions will provide well defined ducts for the penetration of the asphaltum or other composition into the body of the sliver, and during the finishing operation, the expanded portion will be forced to overlay said strands so as to thoroughly protect same.

The operation of the herein described mechanism is substantially as follows:—

In starting a run of the machine, the usual practices are followed, it being possible by separating the parts *d*—*e* to facilitate the threading of the strands *c*³ through the openings *r* and the initial application of the ends of these strands to the sliver covered wire, the die members *f*—*g* having previously compacted the sliver adjacent the discharge end of the die.

To permit the separation of said members *f* and *g*, and the parts *d* and *e*, the slides *o*—*o'* are drawn toward the extensions *m*—*m*² of the fitting *m*, elongating the springs *n*—*n'* sufficiently to permit said slides to be moved laterally from within the open slots of said extensions *m*—*m*².

After the members $f-g$ are closed, the slides $o-o'$ are connected with the slotted extensions $m'-m^2$ by elongating the springs $n-n'$ and merely slipping the slides within

5 said slots.

While the machine is in operation, the entire head c rotates, so that the sliver covered wire passing through the graduated opening $f'-g'$ will be simultaneously 10 smoothed and compacted so that it will be ultimately brought to the diameter of the cylindrical opening f^2-g^2 which will hold the sliver compacted until the binding or covering strands c^3 have been applied there-

15 to.

If it be found that the pressure from the spring rigging is insufficient to hold the die members $f-g$ closed, the tension of the springs $n-n'$ may be increased by means of 20 the nuts $p-p'$, or if it be desired to increase the density of the sliver covering, this result may be secured by increasing the thickness 25 of the sliver applied to the wire and increasing the tension of the springs $n-n'$.

25 In the event of the occurrence in the covered wire of a short length of increased diameter or of a lateral distortion of the wire, which increased bulk will preclude the passage of this portion of the wire through the 30 cylindrical portion f^2-g^2 , the wedging action between this portion of the wire and the walls of the opening $f'-g'$ adjacent the point where it merges into the cylindrical portion f^2-g^2 , will automatically oscillate 35 the members $f-g$ against the tension of the springs $n-n'$ so as to permit the passage of this portion of the wire from the die without applying such longitudinal stresses to the covering sliver as will tend to strip the 40 sliver from the wire.

The turning movement of the die greatly facilitates this wedging action without likelihood of any stripping action upon the sliver. The binding or covering strands c^3 45 will be applied to the large portion of the covered wire in the same manner as to portions thereof of normal diameter.

Instantly with the passage of the enlarged portion of the covered wire from the die, 50 the springs $n-n'$ will close the die members and immediately following such closure, it will resume its normal functioning, the rotation of the die and the pressure of the springs having the effect of completing the 55 compaction of the portion of the covered wire which passed through the graduated opening $f'-g'$ while the members $f-g$ have been opened.

If, during a run of the machine, one of 60 the strips of the sliver, a plurality of such strips being ordinarily employed, should break or become exhausted, and the portion of the wire upon which sliver is not properly applied enters the die, the parts $d-e$ 65 and the members $f-g$ may be separated,

thus permitting access to the portion of the covered wire within the die for purpose of inspection or to facilitate a back-running of the wire, or the breaking of the binding strands to facilitate the formation of the 70 necessary splice in the covering sliver.

A compacting head including a die member as heretofore described, is particularly adapted for use with high speed covering machines, since with the elimination of possibility of stripping by reason of irregularities in the diameter of the covered wire, there is practically no limitation upon the speed of the machine growing out of the 75 functioning of the compacting head. Furthermore, the compacting head may be so set as to adapt it to the covering of wires wherein the insulating body of sliver has different degrees of compaction, the spring tension required with less lightly covered wires not 80 being so great as that required wherein a greater density of the sliver is required.

It is apparent that one die is not adapted for the production of wires of different diameters, the variation in the tension of the 90 springs $n-n'$ being primarily for the purpose of controlling the density of the covering sliver rather than the outside diameter of the covered wire.

It is not my intention to limit the invention to the precise details of construction shown in the accompanying drawings, it being apparent that such may be varied without departing from the spirit and scope 95 of the invention.

Having described the invention, what I claim as new and desire to have protected by Letters Patent, is:-

1. A compacting head for wire covering machines embodying therein a rotatable spindle-carrying platform and a die carried thereby and rotatable therewith including therein opposed members having registering, graduated complementary openings 105 therein, means pivotally supporting said members adjacent the larger portions of said openings, whereby the smaller portions of said openings may have movement toward and from each other, and a spring rigging operative upon said members respectively 110 adjacent the smaller portions of said openings, whereby they will be normally engaged, one with the other, but will automatically separate to accommodate said die to irregularities in the diameter of the covered wire.

2. A compacting head for wire covering machines embodying therein a rotatable spindle-carrying platform and a die carried thereby and rotatable therewith including therein opposed members having registering, graduated complementary openings 115 therein and complementary cylindrical openings into which said graduated openings merge, means pivotally supporting said 120

members adjacent the larger portions of said openings, whereby the smaller portions of said openings may have movement toward and from each other, and a spring rigging operative upon said members respectively adjacent the smaller portions of said openings, whereby they will be normally engaged, one with the other, but will automatically separate to accommodate said die to irregularities in the diameter of the covered wire.

3. A compacting head for wire covering machines embodying therein a rotatable spindle-carrying platform and a die carried thereby and rotatable therewith including therein opposed members movable toward and from each other and having registering, graduated complementary openings therein and complementary cylindrical openings into which said graduated openings merge, said members each having openings therethrough communicating with said cylindrical openings, whereby strands may be passed therethrough and be wound upon the covered wire while held compacted within the die, and a spring rigging operative upon said members respectively, whereby they will be normally engaged, one with the other, but will automatically separate to accommodate said die to irregularities in the diameter of the covered wire.

4. A compacting head for wire covering machines embodying therein a rotatable spindle-carrying platform and a die carried thereby and rotatable therewith including therein a bi-part base, means whereby the separation of the parts of said base is permitted, a die member mounted upon each of said parts to have movement therewith and also to have movement toward and from each other independently thereof, said members having registering, graduated complementary openings therein, a spring rigging operative upon each of said members, whereby they will be normally engaged one with the other but will automatically separate to accommodate said die to irregularities in the diameter of a covered wire, and means whereby said rigging may be disconnected from one of said members to permit the separation of the parts of the bi-part base.

5. A compacting head for wire covering machines embodying therein a rotatable spindle-carrying platform and a die carried thereby and rotatable therewith including therein a bi-part base, means whereby the separation of the parts of said base is permitted, a die member mounted upon each of said parts to have movement therewith and also to have movement toward and from each other independently thereof, said members having registering, graduated complementary openings therein, oppositely disposed brackets carried by said die members respectively, having laterally extending

arms, springs carried by the arms of one of said brackets, a slide connected with each of said springs and entering a slot in the arms of the oppositely disposed bracket, and means carried by said slide and adapted to operatively engage said last named bracket to hold the tension of said springs.

6. A compacting head for wire covering machines embodying therein a rotatable spindle-carrying platform and a die carried thereby and rotatable therewith including therein a bi-part base, means whereby the separation of the parts of said base is permitted, a die member mounted upon each of said parts to have movement therewith and also to have movement toward and from each other independently thereof, said members having registering, graduated complementary openings therein, oppositely disposed brackets carried by said die members respectively, having laterally extending arms, springs carried by the arms of one of said brackets, a screw-threaded slide connected with each of said springs and entering a slot in the arms of the oppositely disposed bracket, nuts co-operating with the screw-threads of said slides respectively and engaging the bracket in which said slides are mounted, whereby said springs may be given any desired tension.

7. A compacting head for wire covering machines embodying therein a rotatable spindle-carrying platform and a die carried thereby and rotatable therewith including a bi-part base, die members pivotally mounted upon the parts of said base respectively, whereby said members have movement therewith and pivotal movement towards and from each other, independently thereof, said die members having registering, graduated complementary openings therein, a spring rigging operative upon each of said die members whereby they will be normally engaged, one with the other but will automatically separate to accommodate said die to irregularities in the diameter of the covered wire, and means whereby the parts of said base may be separated or brought together.

8. A compacting head for wire covering machines, embodying therein a rotatable, spindle-carrying platform and a die carried thereby and rotatable therewith including a bi-part base, die members pivotally mounted upon the parts of said base respectively, whereby said members have movement therewith, and pivotal movement towards and from each other independently thereof, said die member having registering, graduated complementary openings therein, the largest diameter of which is adjacent said base and complementary, cylindrical openings into which said graduated openings merge, said members each having openings therethrough communicating with said cy-

cylindrical openings, a spring rigging operative upon said die members intermediate said base and said cylindrical openings whereby said members will be normally engaged, 5 one with the other, but will automatically separate to accommodate said die to irregularities in the diameter of the covered wire, and means whereby the parts of said base may be separated or brought together.

In witness whereof I have hereunto affixed my signature, in the presence of two subscribing witnesses, this 4th day of October, 1921.

WILLIAM E. COOK.
